UNITED STATES PATENT OFFICE.

CHARLES W. SMITH, OF NORWALK, OHIO.

DESIGN FOR A CURTAIN-POLE BRACKET.

SPECIFICATION forming part of Design No. 21,931, dated October 25, 1892.

Application filed September 26, 1892. Serial No. 446,964. Term of patent 7 years.

To all whom it may concern:

Be it known that I, CHARLES W. SMITH, a citizen of the United States, residing at Norwalk, in the county of Huron and State of Ohio, have invented certain new and useful Improvements in a Design for Curtain - Pole Brackets; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 is a side elevation of a curtain-pole bracket embodying my design, and Fig. 2 is a transverse section on the line $x-x$ of Fig. 1.

My design has reference to brackets for curtain-poles.

My bracket comprises the part A, through which is an opening a for the reception of the curtain-pole, and a shank or stem B. The part

A is globular or spherical in general shape and is carried by the shank or stem B. The latter comprises a straight cylindrical portion b , an outwardly-flaring curved portion b' , the curves being concave, and a short cylindrical portion b^2 , extending from the latter and constituting the base-piece. The portion b^2 is grooved circumferentially, as shown at b^3 , and at the junction of the stem B and the spherical portion A is formed a bead a . A like bead a' is also formed at the diametrically-opposite side of the spherical portion A, from which extends the pointed ornament a^2 .

What I claim is—

The design for a curtain-pole bracket herein shown and described.

In testimony whereof I affix my signature in presence of two witnesses.

CHARLES W. SMITH.
